UNITED STATES PATENT OFFICE.

JOHN TEBBUTT, OF FLORENCE, MASSACHUSETTS, ASSIGNOR TO McCALLUM HOSIERY COMPANY, OF NORTHAMPTON, MASSACHUSETTS, A CORPORATION OF MASSACHUSETTS.

METHOD OF AND MEANS FOR PRODUCING STRIPES IN KNIT GOODS.

1,145,522.

Specification of Letters Patent.

Patented July 6, 1915.

Application filed November 14, 1914. Serial No. 372,183.

To all whom it may concern:

Be it known that I, JOHN TEBBUTT, a citizen of the United States of America, residing at Florence, in the county of Hampshire and State of Massachusetts, have invented certain new and useful Improvements in Methods of and Means for Producing Stripes in Knit Goods, of which the following is a specification.

10 My invention relates to methods of knitting single-needle stripes into full-fashion goods, and means for so doing the same as applicable to so-called fashioning knitting-machines in contradistinction to circular knitting-machines.

The new method consists in leaving slack the loop in the threads at the place where a stripe is to appear in the goods, in rolling the threads in this slack loop, one 20 over the other, to reverse their relative positions, and in completing the stitch; and the new means resides in a divider having a deepened throat to receive the stripe-forming portions of the threads, and provided 25 with a part to assist in turning the threads—all as hereinafter set forth.

In carrying out my method and as a part of the means for so doing I prefer to employ the old elements of an ordinary fashioning knitting-machine, such elements operating in the usual manner.

The primary object of my invention is to produce one or any number of single-needle, vertical stripes in the body of knit goods, by throwing the back threads to the front and the front threads to the back, and to provide a flat, full-fashion machine with practicable and efficient means for doing such work, no additional carriers being required, and there 40 being no extra winding or extra ends or threads.

Heretofore stripes have been superimposed on goods made on the flat, full-fashion machine, so that the goods were thicker in the striped portions, and in order to produce such stripes extra carriers had to be used and besides extra winding had to be done and extra ends or threads were involved.

This invention, as previously observed, enables me to produce flat striped goods, and to do so without the aid of any extra parts except my peculiar or special dividers, which, wherever employed, simply take the places of the ordinary dividers. It is evi-

dent, therefore, that my invention is simple in its nature and economical as well. 55

Practically a limitless number of possible designs and combinations can be produced by my method and with the novel means which I have devised for putting it into 60 practice.

Other objects and advantages will appear in the course of the following description.

To assist me in carrying out my method and attaining the objects and securing the 65 advantages of the invention as a whole, I may employ the means illustrated in the accompanying drawings, in which—

Figure 1 is a top plan of a portion of a flat, full-fashion knitting-machine, with 70 which a number of the thread-reversing dividers is incorporated; Fig. 2, a sectional elevation of such parts of said machine as are required for a clear understanding of the invention, showing with such parts a 75 side elevation of one of said dividers; Fig. 3, a view generally similar to Fig. 2, but without some of the parts shown in the preceding view, and showing the thread-reversing divider in its most advanced position, instead of in its most retracted position as is the case in said preceding view; Fig. 4, a side elevation of a detached jack sinker; Fig. 5, a side elevation of a detached plain divider; Fig. 6, a side elevation of a 80 detached thread-reversing divider; Fig. 7, an enlarged elevation of certain parts illustrating a step in the operation or method; Fig. 8, a similar elevation illustrating another step; Fig. 9, still another elevation 85 illustrative of a further step; Fig. 10, an enlarged elevation of the same parts which appear in the three preceding views, and showing the result produced by the steps previously taken; Fig. 11, an enlarged front 90 elevation or diagram of the thread-engaging parts (exclusive of the carriers and knocking-over bits) disposed substantially as they are in Fig. 3, and, Fig. 12, a top plan of the same. 95

Similar numerals designate similar parts throughout the several views.

The parts of the old machine, which are represented in the drawings, comprise a plurality of jack sinkers 1 and a plurality of 105 dividers 2 mounted to slide horizontally in a member 3, a plurality of striking jacks 4 for said sinkers, a slur 5 by means of which

said striking-jacks are sequentially or progressively actuated, on a pivotal support 6, to advance in a corresponding manner said sinkers, a bar 7 which is designed to advance said dividers simultaneously and in like manner to retract them together with the sinkers, a knocking-over bit 8 that projects forward from said member 3 in the same vertical plane with each divider, and being beneath the forward or forwardly projecting portion of the divider when the latter is in its advanced position, a plurality of needles 9 set in a bar 10 which is capable of moving said needles vertically and horizontally or backwardly and forwardly, and first and second thread carriers 11 and 12, respectively, which in practice travel back and forth, longitudinally of the machine, to lay the threads in behind said needles and across the path of the sinkers. The goods are knit on this machine with the back or inside uppermost and the front or face underneath. The first carrier 11 lays a thread 13 which characterizes the face of the goods and is the front thread, while the second carrier 12 lays a thread 14 which characterizes the back of the goods and is the back thread, the latter always and necessarily following the front thread. Each needle 9 has a spring beard 15 which is closed against an incline 16 on the front of the member 3, when said needle descends. At 17, in Fig. 3, is represented one of the striking-jack springs. Each sinker 1 has a thread-receiving throat 18, and each divider 2 has a similar throat 19, the two throats being in the same horizontal and vertical planes, when the sinker and divider are in their most advanced position; and the upper edges of said sinker and divider, in front of the aforesaid throats, incline downward from back to front at the same angle—see Figs. 4 and 5. Since these parts are old and well known their operation need be only very briefly described. First, the carriers 11 and 12 lay the threads 13 and 14, respectively, and the sinkers 1 are caused to advance successively, through the medium of the slur 5 and the striking-jacks 4, to receive said threads in the throats 18 and indent or loop said threads behind the needles 9, it being understood that, in this machine, there is a pair of needles between each pair of advanced sinkers; then, the dividers 2 are caused to advance all together, through the medium of the bar 7, to receive in their throats 19 the loops previously formed and indent or divide the same by carrying the engaged portions of the threads between the needles in the pairs that are between the sinkers, and the needles are carried down, by the bar 10, to receive within their beards 15, the loops between the sinkers and dividers, there being a loop between each sinker and the adjacent divider, and are moved back to bring

said beards into contact with the inclined part 16 and so close said beards; next, the needles, still descending, draw said loops down through the next preceding loops, which now come to rest on the knocking-over bits 8, to complete the stitches, the sinkers and dividers are all moved back out of the way of the threads, and said needles begin to move forward; and, finally, the sinkers and dividers are advanced once more, this time to prevent the lastly formed loops from rising with the needles, the latter ascend until said loops are held by the needles at points below said beards, and the sinkers and dividers are once more drawn back. Thus the cycle is completed and the mechanism is ready to knit the next row of stitches.

Assuming that the front thread 13 be black and the back thread 14 white, the goods produced by the above described operation will have a generally black face and a generally white back, because the white thread is uppermost at the start, it is above the black thread when they slide off of the front ends of the sinkers and dividers, and said white thread remains on top of the other when the needles finally rise to initial position again. Obviously, then, if the relative positions of these threads be reversed, during the stitch-forming operation, at any point or points, the back thread will appear on the front of the goods in the form of a stripe or stripes, and, of course, a corresponding stripe or stripes, consisting of the front thread, will appear on the back. In order to obtain the result just outlined, I indent or divide the loops that are to form the plain portions of the goods in precisely the same way as before, but, instead of dividing the loops that are to form the striped portions of said goods, and thus stretching or tightening the portions of the threads that form said loops, I leave such loops fairly slack, so that the aforesaid portions of the threads can readily be rolled or turned partly over, and then reverse their relative positions by causing the under thread to mount above the upper thread, and the latter to pass beneath the former. The reversal of the threads, in the present case, is accomplished gradually or by several more or less distinct motions. The under thread is first carried to the rear of the upper thread, then the now forward thread is moved or permitted to move forward and downward ahead of the other, and finally said forward thread is caused to assume a position directly under the thread that was behind; said last-mentioned thread having been underneath initially. From this step in the process or method of knitting, the operation continues in the same manner as before. As a means of accomplishing the desired result and carrying out the new method, or changing the

old method to the new, I employ a thread-reversing divider 20, in place of the ordinary divider, in the machine at each place where it is intended to produce a stripe in the product of said machine. The dividers 20 differ from the dividers 2, in that each of the former has a deep throat 21 and is provided in front of said throat with a convex rolling-surface 22. The throat 21 is deeper than either the throat 18 in any of the sinkers 1, or the throat 19 in any of the dividers 2, and in consequence of this the threads received in said throat 21 are not stretched or held tight as are the threads received in said throats 18 and 19, but are left loose so that they can be reversed; when the divider 20 is retracted, by the contact therewith of the rolling-surface 22, said threads meanwhile being within the beard 15 of one of the needles 9. The dividers 20 operate or travel with the dividers 2, and the same medium is employed to actuate both sets. Four of the dividers 20 are represented in the first view. These dividers are arranged in pairs, and, owing to their number and arrangement, two pairs of stripes are produced in the goods or fabric knit by the machine equipped with said dividers, such stripes showing white on the generally black face of the fabric and black on the generally white back thereof. In this view six of the sinkers 1 have been fully advanced, and three of said sinkers partially advanced, each of the latter being at a different stage in its advancement, while the remaining sinkers therein appearing, the six at the left, are in their fully retracted positions. The dividers 2 and 20 are in their rearmost or fully retracted positions, since they are not advanced until the last sinker is driven forward. As the sinkers 1 advance they receive in their throats 18 the threads 13 and 14, which have been laid in front of said sinkers by the carriers 11 and 12, respectively, with the white thread 14 uppermost, and press said threads forward between every other pair of needles 9 to form, with the aid of said needles, loops 23. The loops 23, which are in the path of the dividers 2, are received in the throats 19 of said dividers, when the latter are driven forward, and thus divided, the middle portions of the threads in each of said loops being carried forward between the pair of needles 9 upon or around which the original loops are formed. Inasmuch as the throats 18 and 19 are all of the same depth and are brought into exact alinement, the loops 23 are divided uniformly, it being understood, of course, that the sinkers 1 and the dividers 2 (or 20) are equidistant from each other. Examples of loops divided in the manner just explained appear at 24 in Fig. 12.

In Fig. 2 one of the sinkers 1 is shown in its most advanced position and in engage-

ment with the threads 13 and 14, one of the dividers 20 is shown in initial position, and the needle 9 shown is represented in its forward and upward position, the position of all of the needles at this time. A portion 70 of the knit fabric is represented at 25 in this and the next view.

Passing to Fig. 3 it will be observed that the sinker 1 and the needle 9 therein shown are in positions which correspond to those 75 which they occupy in the preceding view, but that the divider 20 shown in said Fig. 3 is in its most advanced position, with the threads 13 and 14 in the throat 21. Referring now to Figs. 11 and 12, in connection 80 with Fig. 3, it is seen that, when the dividers 2 and 20 are advanced, the former produce the loops 24, by dividing the loops 23 which were previously produced by the sinkers 1 when advanced, in the manner already explained, and that said dividers 20 leave the loops 23 which are in front of them without actually dividing or at least without stretching or tightening the threads at 85 these points, owing to the fact that said threads are received in the deep and rearwardly positioned throats 21, that is, deep and rearwardly positioned relative to the adjacent throats 18 and 19. It is clear, therefore, that those portions of the threads 90 that pass through one of the throats 21, back of two needles 9, and then divergently forward to the sinkers on both sides of said needles, must be comparatively slack. Owing to the downward and rearward inclination of the edges of each throat 21, the threads may be drawn slightly out of a horizontal plane, as appears to be the case at 26 in Fig. 11, but this divergence is not sufficient materially to tighten said threads or 95 to interfere with the subsequent rolling and reversing. The needles 9 now descend from the position indicated in Fig. 3, until the threads 13 and 14 are in the spaces in front of the beards 15, as shown in Fig. 7. With 100 the threads, the white still above the black, within the boards 15 of the two needles 9 between which each divider 20 is positioned, said needles move downwardly and rearwardly to close said beards against the inclined part 16, and said divider begins to move back, as indicated in Fig. 8. When the divider 20 moves back, the rolling-surface 22 thereof in sliding beneath the thread 110 13 carries or rolls said thread from beneath the thread 14, said threads being at this time confined in the upper parts of the needle eyes on both sides of said divider, but not at the extreme upper ends of said eyes. As the aforesaid rolling-surface and the front terminal of the divider 20 continue to slide under the threads 13 and 14, the latter precedes the former and finally slides 115 down off of the front end of said divider followed by the thread 13. Just before this 120 125 130

occurs, the threads in the preceding loop 27, which before were supported by the shanks of the needles below their beards, are forced onto said beards, which latter are now closed. This operation or result is brought about by the descending needles and with the aid of the knocking-over bit 8 under-said loop. The threads 13 and 14, the latter underneath the former, are now confined 10 in the narrow spaces at the upper ends of the needle eyes, and the needles descend farther and move forward to release their beards, as represented in Fig. 9. The divider 20 having been fully retracted so as 15 to be out of the way, the needles complete their descent and draw the reversed threads through the loop 27 of reversed threads below, and so complete the stitch. Next the needles ascend and move forward into initial 20 position, and the divider 20 moves forward to hold down the last loop, as illustrated in Fig. 10. In this way and by this means the needle beards pass above the last loop, and the latter is supported by the 25 shanks of the needles below said beards. Finally the divider 20 moves back, with the other dividers and the sinkers, to initial position, in readiness for the reversal of the threads in the next following loop and the 30 making of the next following stitch, after the sinkers have again made their initial or first forward stroke in a cycle.

It will be observed that the stripe stitches are made in the same way as are the other 35 stitches, with this important distinction: Prior to the completing of the loop stitch for the stripe, that is, before any last loop formed by a pair of sinkers and a divider 20 is released by said sinkers and divider, 40 when the same are drawn from beneath said last loop, and the latter is drawn through the preceding loop on the needles, the threads in said last loop are reversed, being reversed by the action of said divider thereon and because said threads are left 45 loose or slack; while in the case of any stitch in the unstriped portion of the fabric, although a pair of sinkers and a divider 2 are drawn from beneath said last-mentioned 50 stitch, it is not reversed and can not be reversed, since it is held taut by said last-mentioned sinkers and divider, and the back thread, which at the start is on top of the front thread, remains in that position 55 continually. It follows, therefore, that my invention resides in leaving slack and rolling, turning, or reversing the stripe-forming loop threads, and in the means for so doing, as has previously been stated.

60 The knocking-over bits 8 are omitted from the first view.

Many of the parts and members herein shown are necessarily exaggerated in size and thickness, for reasons which will be 65 readily understood.

Although I have disclosed a practical and efficient embodiment of my invention, I do not desire or intend to be unduly restricted thereby, or to be limited in the scope of said invention because of such disclosure, it being clearly apparent to one skilled in the art 70 that mechanical modifications and changes may be made without departing from the spirit of the invention.

What I claim as my invention, and desire 75 to secure by Letters Patent, is—

1. The method of producing stripes in knit goods, consisting in feeding a plurality of threads, in forming such threads into loops and leaving comparatively loose the threads comprising one loop, while the threads in another loop are kept taut, and in reversing said loose threads. 80

2. The method of producing stripes in knit goods, consisting in feeding a plurality of threads, in forming such threads into loops and leaving comparatively loose the threads comprising one loop, while the threads in another loop are kept taut, and in turning said loose threads to reverse 85 them. 90

3. The method of producing stripes in knit goods, consisting in laying the threads, in indenting said threads to loop them, in leaving the portions of threads in the stripe-forming loops comparatively slack, in turning said portions of threads to reverse them, and in completing the stitch with said portions of threads reversed. 95

4. In the art of producing stripes in knit goods, means to feed and form threads into loops and to hold the threads in certain loops taut without tightening the threads in certain other loops, the latter being stripe-forming loops, and means to turn and reverse the threads in the untightened loops. 100

5. In the art of producing stripes in knit goods, reciprocal means to form threads into loops and to hold the threads in certain loops taut without tightening the threads in certain other loops, the latter being stripe-forming loops, and reciprocal means to turn and reverse the threads in the untightened loops. 105

6. The combination, in means for producing stripes in knit goods, with stitch-holding means, of a reversing divider having a rolling-surface with which said stitch-holding means co-operates to reverse the threads by frictional contact of the latter with said rolling-surface. 110

7. The combination, in means for producing stripes in knit goods, with stitch-holding means, of a reversing divider adapted to receive and engage threads without straining them, and having a rolling-surface with which said stitch-holding means co-operates to reverse said threads by frictional contact of the latter with said rolling-surface. 115 120 125 130

8. The combination, in the art of producing stripes in knit fabric, with thread-laying means, thread-indenting means, and stitch-completing means, of a thread-reversing member having a deep throat to receive and retain threads in a comparatively loose condition.

9. The combination, in the art of producing stripes in knit fabric, with thread-laying means, thread-indenting means, and stitch-completing means, of a thread-reversing member having a rolling-surface to reverse the threads with which such surface is brought into contact.

10. The combination, in the art of producing stripes in knit fabric, with thread-laying means, thread-indenting means, and stitch-completing means, of a thread-reversing member having a deep throat to receive and retain threads in a comparatively loose condition, and provided with a rolling-surface to reverse said threads by frictional contact.

11. The combination, in means for producing stripes in knit fabric, with a plurality of needles, thread-laying means, a plurality of sinkers, and a plurality of dividers, said sinkers and dividers having throats of corresponding depth, of a reversing divider having a throat which is deeper than said first-mentioned throats.

30

12. The combination, in means for producing stripes in knit fabric, with a plurality of needles, thread-laying means, a plurality of sinkers, and a plurality of dividers, said sinkers and dividers having throats of corresponding depth, of a reversing divider having a throat which is deeper than said first-mentioned throats, said reversing divider being provided in front of said throat with a thread-rolling surface.
